W. S. JOHNSON ET AL

ELECTRIC RIVET HEATER

Filed Feb. 28, 1921

INVENTORS:
William S. Johnson, and
John W. Sheffer
BY *J. H. Giles*

ATTORNEY.

UNITED STATES PATENT OFFICE.

WILLIAM S. JOHNSON AND JOHN W. SHEFFER, OF BERWICK, PENNSYLVANIA, AS
SIGNORS TO AMERICAN CAR AND FOUNDRY COMPANY, OF ST. LOUIS, MISSOURI,
A CORPORATION OF NEW JERSEY.

ELECTRIC RIVET HEATER.

Application filed February 28, 1921. Serial No. 448,313.

To all whom it may concern:

Be it known that WILLIAM S. JOHNSON and JOHN W. SHEFFER, residing at Berwick, Columbia County, Pennsylvania, and being citizens of the United States, have invented certain new and useful Improvements in an Electric Rivet Heater, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

In said drawings:

Figure 1 is a front elevation of a portion of an electric rivet heater showing our improvement applied thereto;

Figure 2 is an elevation, partly in section, of a portion of the structure shown in Fig. 1; and

Figure 3 is a side elevation, partly broken away, of the parts shown in Fig. 2.

It is an object of our invention to provide an electric rivet heater having its secondary coil provided with electrodes adapted to be adjusted relatively to each other so as to accommodate rivets of different lengths and it is a further object of our invention to provide a simple and efficient means whereby the electrodes may be quickly adjusted to provide the desired normal opening between the electrodes.

In the drawings, 1 designates the primary coil, 2 the secondary coil and 3 the separators interposed between the primary and secondary coils. The coils 1 and 2 and the separators 3 are mounted upon the upper portion of the rectangular laminated core 4 carried upon a suitable base (not shown) and held between pairs of members 6 and 7 which are held tightly against the core by the bolts 8, the members 6 being secured by bolts 8 to the members 7 which are, in turn, secured to the base.

Secured to members 6 by the bolts 8 is a U-shaped angle bar supporting member 9 that passes over the coils 1 and 2. The sup-

porting member 9 is secured to the members 6 so that, of the portion of the member 9 extending over the coils 1 and 2, one flange 55 will be horizontal and project over the upper electrode 10 of the secondary coil 2 while the other flange will project downwardly from the horizontal flange as shown in 60 Fig. 3.

The upper electrode 10 has a screw threaded opening 11 in which is threaded a rod 12 having a portion 13 threaded to engage in the opening 11 and the remainder of the rod 65 provided with a screw thread 14 of a coarse pitch. The rod 12 projects through an opening in the horizontal flange 15 of the supporting member 9 and is provided with the lock and adjusting nuts 16 and 17, adapted 70 to engage the opposite faces of the horizontal flange 15. Pivotedly secured to the nut 17 is an operating handle or wrench 18 comprising a handle 19 secured to a yoke 20, the sides of the yoke 20 extending on opposite sides of the nut 17 and being secured thereto by bolts 21 which are threaded into the sides of the yoke 20 and have cylindrical ends fitting into openings in the nut 17.

The lower electrode 22 of the secondary 80 coil is operated by means of a rod 23 pivotally connected to an operating lever (not shown) at its lower end and by a bolt 25 to a lug 24 secured to the electrode 22 at its upper end.

The electrode 10 is adjusted to vary the gap between the electrodes 10 and 22 by loosening the nut 17 whereupon the nut 16 may be readily turned to its new position without using a wrench or other tool after 90 which the electrode 10 is moved to its new position and locked in place by tightening the nut 17.

Pivoting the wrench to the nut 17 prevents the wrench from becoming lost and permits 95 of it being turned to a position opposite to that shown in Fig. 3 so as not to interfere with the operation of the machine.

What we claim is:

1. An electric rivet heater having a secondary coil, a normally fixed upper electrode on said coil, a support for said electrode, threaded means connecting said electrode and said support and means on said threaded means and engaging on opposite 100 sides of said support adapted to adjust the

position of said electrode with respect to said support and to lock said electrode in fixed position.

2. An electric rivet heater having a secondary coil, upper and lower electrodes for said coil, a supporting member having an opening therein, a threaded member secured to said upper electrode and passing through said opening in said supporting member to 10 suspend said upper electrode therefrom and means on said threaded member adapted to engage said supporting member to shift said electrode with respect to said supporting member.

15. 3. An electric rivet heater having a secondary coil, upper and lower electrodes for said coil, a supporting member having an opening therein, a threaded member secured to said upper electrode and passing through 20 said opening in said supporting member to suspend said upper electrode therefrom, a nut on said threaded member in engagement with said supporting member, operating means for said nut pivotally connected thereto and means adapted to cooperate 25 with said nut in locking said threaded member in fixed position.

4. An electric rivet heater having a secondary coil, upper and lower electrodes on 30 said coil, a supporting member having an opening therein, a threaded member secured to said upper electrode and passing through said opening in said supporting member to suspend said upper electrode therefrom, means on said threaded member 35 adapted to engage said supporting member to shift said electrode with respect to said supporting member and means cooperating

with said shifting means and said supporting member to lock said threaded member in fixed position.

5. In an electric rivet heater, a secondary coil having a normally fixed upper electrode, a supporting member having an opening therein, a threaded member secured to 45 said upper electrode and passing through said opening in said supporting member to suspend said upper electrode therefrom, means on said threaded member engaging on one side of said supporting member to 50 shift said electrode with respect to said supporting member and means cooperating with said shifting means and said supporting member and engaging on the opposite side of said supporting member to lock said 55 electrode in fixed position.

6. In an electric rivet heater, a secondary coil having a normally fixed upper electrode, a supporting member having an opening therein, a threaded member secured to 60 said upper electrode and passing through said opening in said supporting member to suspend said upper electrode therefrom and means on said threaded member and engaging on opposite sides of said supporting 65 member to shift said electrode with respect to said supporting member and to lock said electrode in fixed position.

In witness whereof we have hereunto set our hands in the presence of two witnesses.

WILLIAM S. JOHNSON
JOHN W. SHEFFER.

Witnesses:

FRED A. HOFFMAN,
HENRY F. TRAUGH.
